STAPLE-APPLYING IMPLEMENT

Arthur H. Maynard and George H. Harred, Warwick, R. I., assignors to Boston Wire Stitcher Company, Portland, Maine, a corporation of Maine

Application November 30, 1934, Serial No. 755,252

21 Claims. (Cl. 140—55)

This invention relates to stapling or fastener-applying implements for use in connecting sections of wire fencing, netting and other reticulated wire fabrics and also for binding together 5 wires, ropes and other like materials.

One object of the invention is to provide a novel 10 implement of the type indicated in the form of pliers having opposed jaws for gathering and holding the parts of the work, a magazine for containing and feeding staples, and mechanism for driving the staples into position and clinching them around the work.

Another object of the invention is to provide an 15 implement of the type indicated wherein the staple-driving and clinching mechanisms are manually operated from a pair of handles connected in the manner of a toggle joint to increase their leverage and reduce the force and effort required to operate the device.

Still another object of the invention is to provide 20 an implement of the type indicated in which an enclosed staple magazine may be conveniently loaded or charged with staples without dismantling its parts or opening the closure.

Another object of the invention is to provide a 25 portable implement of the type indicated which is compact and simple in construction, positive and efficient in operation and capable of extended use without repair or adjustment.

These and other objects will become apparent 30 from the following description and drawings in which a preferred embodiment of the invention only has been described, by way of example, as illustrated by the accompanying drawings.

In the drawings:

Fig. 1 is a perspective view of the improved implement illustrating the manner of applying it to use for connecting the ends of wire fence sections or the like;

Fig. 2 is a partial front view of the jaws of 40 the implement showing them opened to receive the wires to be fastened together;

Fig. 3 is a similar view showing the relationship of the parts during the gathering of the fence-wires and the driving of a staple;

Fig. 4 is a similar view illustrating the relationship of the parts at the completion of the stapling operation;

Fig. 5 is a side view of the implement with a 50 portion of its magazine casing broken away to show the staple-feeding means;

Fig. 6 is a side view of the rearward end of the magazine similar to Fig. 5 illustrating the method 55 of loading it with staples;

Fig. 7 is a rearward end view of the implement;

Fig. 8 is a sectional elevational view of the fore part of the implement taken on line 8—8 of Fig. 3 and showing the relationship of the parts of its 5 mechanism during the staple-driving operation;

Fig. 9 is a plan view of the implement shown in Fig. 1 with the ends of the operating handles broken away;

Fig. 10 is a part sectional plan view of the fore 10 part of the device taken on line 10—10 of Fig. 3;

Fig. 11 is an enlarged cross-sectional view through the staple-magazine taken on line 11—11 of Fig. 5;

Fig. 12 is a sectional plan view of the clinching 15 jaws taken on line 12—12 of Fig. 4;

Fig. 13 is a perspective view of the staple-pusher;

Fig. 14 is a perspective view showing a series 20 of staples as used in the device;

Fig. 15 is a perspective view illustrating the manner in which a number of parallel wires are bound together by means of a staple applied by the present device; and

Fig. 16 is a similar view illustrating the method 25 of binding crossed wires.

In general, the present stapling device comprises a magazine for holding a supply of staples, means for successively feeding the staples from the magazine, and means for operating upon the 30 individual staples as they are delivered from the magazine to drive them into place to be clinched around the work. In addition thereto means are also provided in the form of opposed jaws for drawing a plurality of strands or parts of the 35 work together and clinching the staples in position as they are driven. Further, the invention includes means for simultaneously operating the staple-driver and clinching means in the form of handles so connected as to form a toggle arrangement to facilitate the operation of the 40 implement.

Referring now to the drawings where the present fastener appliance is illustrated as comprised of a frame in the form of an enclosed magazine 45 casing 2 for holding a supply of staples, and a stapling head 3 at its forward end in which the stapling mechanism is incorporated. As shown particularly in Figs. 5 and 11 of the drawings, the casing 2 is of rectangular form in cross-section 50 having a bottom 4 and side walls 5 bent upwardly therefrom. The side walls 5 are then folded inwardly at the top with their edges spaced slightly apart to provide a longitudinal slot 6 extending substantially the entire length of the casing. 55

Referring now to Figs. 5 and 7 where the rearward end of the magazine is shown as closed by flanges 8 bent inwardly from the side walls 5. The bottom 4 and side walls 5 are cut away at this end to provide an opening 9 through which the staples s may be inserted in filling or charging the magazine as will later appear. At the forward end of the magazine the side walls 5 are extended upwardly to form spaced wing portions 10 for embracing and holding a block 12 by means of screws 11, which, in turn, support the head 3 including the operative mechanism for driving and clinching the staples. The rearward end of the device is supported on a pair of legs or skids 13 formed as the opposite looped sides of a wire 14 welded to the sides and rearward end of the casing 2.

A staple-core 15 for slidably supporting the staples to adapt them to be fed individually to the driving mechanism is secured within the casing 2 and to the bottom 4 by means of screws 16. The staple-core 15 extends to the forward face of the block 12 at one end but terminates short of the end of the casing at its opposite end with a portion projecting into the opening 9 to facilitate insertion of the staples. In the preferred embodiment illustrated the staples used are of a novel and unusual shape in that each staple s has a flat top or crossbar and depending legs which are bent to form an obtuse angle with the crossbar and so that they slope diagonally outward. The lower ends of the legs are then bent inwardly so that the legs of the resulting staple are of a generally rounded contour with the ends spaced to form an opening of greater width than the width of the crossbar. The staples may be separately placed on the core but preferably the individual staples are cemented together with a suitable material at their edges to form a bar or stick of a plurality of staples. As shown in Fig. 11 the core 15 is similarly shaped to receive this form of staple being provided with an enlarged longitudinally extending body or top portion 17 and a reduced shank portion 18 adjacent the bottom 4 of the casing. The enlarged body portion is so constructed as to provide laterally extending ribs 19 that are beveled to form angular bearing surfaces against which the sloping portions of the legs of the staples s engage. It will be seen by reference to Fig. 11 that the lower converging ends of the legs of the staples engage the under side of the ribs 19 and are thus prevented from moving upwardly from the core. With this form of staple and core the staples cannot overlap each other or become twisted on the core which substantially eliminates improper operation of the implement.

The staples s are urged forwardly along the core to deliver them to the driving mechanism by means of a staple-pusher indicated generally by the reference character 20. As shown in Fig. 11, the staple-pusher comprises a U-shaped sheet-metal member or carriage 21 with spaced pins 22 extending through the sides to form bearing spindles for rollers 24 on which the carriage is mounted for longitudinal movement in the magazine casing. To this end channel-shaped tracks or guideways 25 for the rollers are provided within the casing on the opposite side walls, that extend substantially the entire length of the casing so that the carriage may be moved to the extreme end of the magazine and beyond the end of the staple-core. The carriage 21 is also provided with an upwardly reaching arm 26 which passes through the slot or opening 6 of the magazine and has a knob 27 attached to the outer end

that serves as a finger-grip for manually sliding the pusher 20 rearwardly.

Riveted or otherwise secured to the under side of the carriage 21 is a sheet-metal member 30 shown in detail in Fig. 13. The member 30 is of inverted trough shape with its inclined sides adapted to overlie the sloping sides of the staple-core 15. Riveted to the inclined sides of the member 30 are resilient pusher-fingers 32 which extend forwardly therefrom with their ends bent inwardly at a slight angle for contacting the rear-most staple s of the series mounted on the core 15 as shown in Figs. 5, 10 and 11. The corners of the bent portions of the fingers 32 are folded upwardly as indicated at 33 to provide abutments for engaging against the staple and to prevent the edges of the fingers 32 from wedging in under the strip of staples. The pusher carriage 21 is also provided with a pin 34 to which is hooked one end of a helical spring 35 that extends forwardly around a roller 36 rotatably mounted on a stud 38 between the sides of the casing 2, and then reaches rearwardly with its end anchored to a pin 37 rigidly secured in one of the side walls 5 as shown in Fig. 11. The pusher 20 is manually drawn rearwardly to engage its fingers 32 with the end of the strip of staples s and to prevent the staples from being ejected from the magazine during this movement a latch-detent 40 is provided. As shown in Figs. 5, 6 and 7, the latch 40 is fitted within a slot 41 in the end of the core 15 and pivoted on a transverse pin 42 driven through the end of the core and extending across the slot. The latch 40 is formed with a pointed toe 43 which is normally projected above the top of the core under the action of a spring-pressed plunger 45 slidably arranged in a hole 46 at the bottom of the slot 41. The upward swinging movement of the latch under the action of the plunger 45 is limited by the engagement of a projection 48 of the latch with the end of the slot 41.

The head construction fixed to the block 12, as shown in Fig. 8, comprises a guide-plate 51 abutting the forward end of the block 12 and is provided in its front face with a vertical slot or guideway 52 in which a reciprocable staple-driver 50 is adapted to slide. In the rearward face of the plate 51 is a shallow transverse groove 53 which cooperates with a deeper slot 54 in the front side of the block 12 in forming a rectangular aperture for receiving a back pivot-plate 55, the ends of which project beyond the sides of the casing 2 for a purpose as later explained. The guide- and pivot-plates 51 and 55 are secured in place against the block 12 by means of rivets 58, as shown in Figs. 4 and 10. Referring now to Figs. 4 and 8, the bottom of the block 12 is spaced from the top of the core 15, and the plate 51 is provided near its lower end with a rectangular aperture 59 forming a throat 49 surrounding the core and through which the staples s pass into the guideway 52 beneath the staple-driver 50. As shown in Fig. 8, the lower edge of the plate 51 forming the opening 59 is fitted into a recess 61 in the forward bottom edge of the staple-core 15.

The staple-driver 50 consists of a flat strip or blade of hardened metal having its lower end narrowed slightly and formed with a groove 62 at the bottom conforming to the contour of the top of the staples. The driver 50 is slidably held in the guideway 52 of the plate 51 by means of a face-plate 60 of the same general outline as the plate 51.

The front of the face-plate 60 is formed with a transverse groove 64 for receiving a forward piv-

ot-plate 65 to which it is fastened by rivets 66, see Figs. 2, 5 and 10. Welded or otherwise secured to the front of the face-plate 60 below the pivot-plate 65 is a combined work-guide and support 68. In the bottom of the support is a groove 69 the sides of which slope outwardly to guide the work into place in the bottom of the slot when the implement is applied to use in the manner as later explained.

10 Referring to Fig. 10, the front pivot-plate 65 together with its attached face-plate 60 is secured to the back pivot-plate 55 by means of bolts 70 passing through alined holes in the ends of the two plates. Positioned on the bolts 70 between 15 the plates 65 and 55 are bushings 71 which serve to maintain the plates in spaced relationship and provide pivots for the clinching levers 80 to be presently described. Nuts 72 screwed onto the projecting threaded ends of the bolts 70 hold 20 the several parts together.

Secured within a vertical groove 14 in the rearward face of the plate 60 by means of a screw 76 is a staple-supporter 75, as shown in Fig. 8. The supporter 75 is constructed from relatively 25 thin spring metal and has its lower free end bent rearwardly to bear against the forward end of the staple-core 15 beneath the driver 50 and between the legs of the foremost staple *s* on the core. When the leading staple *s* is severed from the 30 strip by the driver 50 and driven downwardly in the guideway or slot 52 the supporter acts to hold it firmly against the bottom of the driver and preventing it from dropping out of the device. Should the stapling operation be interrupted after the staple is partially driven the 35 supporter 75 holds the staple suspended in the guideway 52 to prevent the feeding of another staple *s* into the guideway before the first staple has been completely driven.

40 Referring now to Figs. 1, 2 and 10 where the clinching levers 80 are shown as comprising upper and lower arms 81 and 82, respectively, extending in opposite directions from a central hub portion. The hub portions are provided with 45 bearing apertures by means of which the levers are pivotally mounted on the bushings 71 between the front and back pivot-plates 65 and 55. The arms 82 are narrowed toward their bottom end, and have inwardly directed jaws 83 with 50 curved recesses on their inner faces to form an open pocket therebetween. The recessed faces of the jaws 83 are scored with substantially arcuate clinching grooves 85 for receiving the legs of the staples *s* as they are driven and bending them 55 about the work.

Referring now to Fig. 12 where the clinching grooves 85 are shown as offset with respect to each other with the groove in one of the jaws inclining forwardly and the groove in the other jaw inclining rearwardly with respect to a medial plane through the two jaws parallel to their faces and with each jaw being provided with a continuation of the offset groove in the opposite jaw. With this construction and arrangement of the 65 grooves the legs of the staples *s* are caused to pass by each other as they are bent around the work to an offset and overlapping position.

The staple-driver 50 and clinching levers 80 are operated manually by a pair of hand levers 70 75 connected therebetween. As shown in Fig. 1, the levers 88 are of an inverted T-shape configuration in outline, being formed with laterally extending links 89 at their bottoms. The inner end of the link 89 of one of the levers 88 is bifurcated 75 as at 90 to receive a tongue 91 formed at the end

of the opposite link 89, the tongue of the latter link being slit at 92 to receive the upper end of the staple-driver 50. A bolt 93 passes through alined bearing apertures in the three elements and is held in place by a nut 94 to pivotally connect the elements together. 5

Referring now to Figs. 1, 2 and 5, it will be observed that the outer end of each link 89 is bifurcated to receive a bushing 95 which is mounted on a bolt 96 passing through bearing apertures in the 10 link. The outer end of each of the levers 80 is provided with a bearing aperture for receiving the bushing 95 on the bolt 96 to form a pivotal connection with its respective link, and the bolt is held in place by means of a nut 97 screwed onto its 15 threaded end. The implement having now been described in detail its method of operation will next be explained.

To prepare the stapling implement for operation the magazine is first loaded by passing staples *s*, preferably in the form of a strip or stick, through the opening 9 and onto the core 15, the end of which terminates adjacent the opening to facilitate the loading of the magazine. When the magazine is empty the staple-pusher 20 is at rest 20 against the block 12 and after the strip of staples has been positioned on the core the pusher is manually moved to the rear of the magazine by means of the hand knob 21 so that the spring-fingers 32 may engage the end of the stick. As 25 the staple-pusher is withdrawn its resilient fingers 32 press against the strip of staples to carry the latter rearwardly until its end encounters the toe 43 of the detent 40. At this time the strip is restrained from further movement and 30 continued rearward movement of the pusher causes the fingers 32 to yield and ride over the individual staples *s* and finally snap into place at the rear of the staple strip in the manner as 35 indicated by dash lines in Fig. 6. The staple-pusher is then released and by the action of the coil-spring 35 is drawn forwardly to feed the staples to the driving mechanism. The stapling 40 implement is then ready for operation.

Assuming that it is desired to connect two sections of wire-fencing or other reticulated wire fabrics such as those indicated at F in Fig. 1, the end wires *w* of the sections are first laid in closely parallel relationship upon a flat surface. In forming earth-retaining strips for use in constructing waterway embankments and similar engineering projects the end wires *w* of the sections F are usually reinforced by a larger wire or cable *W* to which they are secured. The reinforcing wire *W* is set between the end wires *w* and the 50 stapling implement placed thereover with the three wires entered between the open jaws 83 of the levers 80. When the implement is placed in position in this manner its forward end is supported by the lower ends of the jaws 83 while its 55 rearward end is held elevated by the skids 13.

To operate the implement to drive and clinch a staple in binding engagement around the wires *w* and *W*, the operator grasps the ends of the handle-levers 88 and draws them together. As the 65 levers 88 are brought together the links 89 at their ends operate in the manner of a toggle to simultaneously actuate the jaws 83 and staple-driver 50. Outward swinging movement of the links 89 causes pivotal movement of the levers 80 on 70 the fulcrums 10 to carry the lower jaw ends 83 inwardly. As the jaws 83 move inwardly the wires *w* and *W* are gathered together in the pocket formed by the recessed portion of the jaws 83 and the groove 69 of the support plate 68. The 75

wires are thus held firmly on three sides in position to receive a staple *s* which is driven into engagement with the wires by the staple-driver.

- Concurrent with the work-gathering operation 5 the driver 50 is forced downwardly in the guideway 52 under the swinging action of the handle-levers 88. As the driver 50 descends its bottom edge severs the foremost staple *s* from the strip or stick and drives it downwardly in the guideway 10 52. During the driving of the staple the supporter 75 yieldably presses against the head or crossbar thereof to prevent it from falling out of the stapling head.

As shown in Fig. 2 of the drawings, the lower 15 edge of the staple-driver 50 is initially held at a considerable distance above the top of the core 15 so that the jaws 83 will have completely gathered the wires together before the driver 50 has reached its lowermost position. When the driver 20 50 has engaged and driven the staple *s* to such an extent that its legs project below the bottom of the guide-plate 51 the jaws 83 will have swung into position to receive the legs in the clinching grooves 85, see Fig. 3. As the legs of the staple *s* 25 enter the grooves 85 they straddle the wires *w* and *W* held between the jaws 83 and further movement of the handle-levers 88 causes the jaws 83 to meet in abutting relationship and the driver 50 to drive the crossbar of the staple *s* against 30 the wires *w* and *W*. During the downward movement of the staple *s* to its final position its legs are guided around the wires by the clincher-grooves 85 as illustrated in Fig. 4 to firmly clinch and bind the wires securely together. Further, 35 due to the offset relationship of the grooves 85, the legs of the staple *s* are caused to pass by each other to an offset overlapping position as shown in Fig. 15 and the wires or other work are effectively clamped together to withstand considerable strain.

After the wires *w* and *W* have been secured together in the manner as above outlined, the handle-levers 88 are manually drawn outwardly to the position illustrated in Fig. 1 to reset the 45 device for another stapling operation. As the jaws 83 are opened the driver 50 ascends to a position above the staple-core 15 as shown in Fig. 2 and the staple-pusher 20 is urged forwardly by the coil-spring 35 to feed another staple *s* 50 into the guideway 52 beneath the driver 50 to be subsequently applied to the work. When wire fence-sections are being joined together, the end wires *w* thereof are stapled at spaced intervals therealong and after each stapling operation the 55 various operating parts of the implement are reset for the next operation.

In Figs. 1 to 15, inclusive, the device is shown as applied to use in stapling wires together but it is to be understood that it is equally efficient in 60 fastening rods, bars, ropes, strands of any kind or other work together. When crossing wires or the like are to be fastened together the implement is placed thereover with its jaws 83 arranged diagonally across the wires and a staple *s* 65 applied thereto in the manner illustrated in Fig. 16.

It will now be apparent to one skilled in the art that the present invention provides a particularly simple and efficient implement for connecting strands such as sections of wire, fencing, netting and other reticulated wire fabrics and also for binding together wires, ropes and other objects; and also an implement that is portable and easily transported to operative positions.

75 It will also be apparent that the present in-

vention provides an implement for easily connecting or binding a plurality of articles with a strong and durable material by a simple manual operation, due to the toggle arrangement, the clinchers, and the preformed staple; and which 10 will positively clamp and bind the work with a minimum effort. It will also be apparent that an implement has been provided which may be easily and quickly loaded with staples without dismantling any of its parts.

While we have herein shown the device as embodied in a preferred form of construction only, it is to be understood that various modifications may be made in the structure and arrangement of its parts without departing from the spirit or 15 scope of the invention. Therefore, without limiting ourselves in this respect, we claim:

1. In a stapling machine, the combination of a head, a staple-driver in said head for driving staples into engagement with the work, clincher-jaws mounted on said head independently of the staple-driver, and means directly connected to the staple-driver and clincher-jaws and operative to simultaneously actuate the same to drive a staple and clinch the ends of its legs in binding engagement with the work.

2. In a stapling machine, the combination of a head, a staple-driver mounted for reciprocation in said head, clincher-jaws mounted on fixed pivots at opposite sides of the head and independently 30 of the staple driver, said clincher-jaws being adapted to swing to a closed position below the staple-driver, means for feeding staples to said reciprocating staple-driver, and hand-levers directly connected to the staple-driver and clincher-jaws for simultaneously actuating the same.

3. In a stapling machine for connecting or binding a plurality of strands, the combination of a staple-driver for driving staples into engagement with the strands, pivoted jaws mounted for 40 swinging movement to a position below the staple-driver, means cooperating with the jaws for gathering and holding the plurality of strands, and a common means directly connected to both the staple-driver and pivoted jaws and operative 45 to simultaneously actuate the same to gather the strands and clinch a staple in binding engagement with the strands.

4. In a stapling machine for connecting or binding a plurality of strands, the combination of a head, a staple-driver mounted for reciprocating movement in the head, a pair of jaws pivotally mounted on opposite sides of the head and adapted for swinging movement to a position below the staple-driver, the bottom of said head cooperating 50 with the jaws to form a pocket in which the strands are gathered, and a pair of hand-operated levers directly connected to both the staple-driver and the jaws to form a toggle for simultaneously actuating the staple-driver and jaws to gather the strands, drive a staple and clinch the legs of the staple in binding engagement with the strands.

5. In a stapling machine, the combination of a staple-driver for driving staples into engagement with the work to be stapled, pivoted jaws mounted 55 on opposite sides of the staple-driver for swinging movement into cooperative relation with the staple-driver, and a pair of cooperating lever handles having links directly connected with the staple-driver and pivoted jaws, said lever handles 70 being adapted to simultaneously actuate the staple-driver and pivoted jaws to drive and clinch a staple into binding engagement with the work.

6. In a stapling machine, the combination of a head, a staple-driver mounted for reciproca- 75

tion in said head, clincher-levers pivotally mounted on the sides of said head and having jaws at one end for engaging and clinching the ends of a staple, toggle-levers pivotally connected to each other and to the staple-driver at one of their ends and to the clincher-levers at their other ends, and means for simultaneously actuating both the staple-driver and the clincher-jaws.

7. In a stapling machine, the combination of a head, a staple-driver in said head, clincher-jaws mounted on said head and cooperating with said staple-driver to clinch the ends of a staple, guideways in said jaws for directing the ends of the staple to an offset overlapping relationship, means for supplying staples to the staple-driver, and toggle levers pivotally connected to each other and to the staple-driver at one of their ends and to the clincher-jaws at their opposite ends for simultaneously operating the staple-driver and the clincher-jaws to drive a staple into engagement with the material to be stapled and clinch the ends of the staple in an offset overlapping engagement.

8. In a stapling machine, a head, a staple-driver mounted for reciprocation in said head, jaws pivotally mounted on said head and on opposite sides of the staple-driver for swinging movement to a position below said head, guideways in said jaws for directing the ends of a staple into binding engagement with the work in an offset overlapping relationship, means for successively feeding staples to the staple-driver, and manually operable handles having links pivotally connected to each other and to the staple-driver at one of their ends and to the jaws at their opposite ends for simultaneously actuating the staple-driver and the pivoted jaws to drive a staple and clinch its ends in an offset overlapping position.

9. In a stapling machine, mechanism for clinching the ends of a staple in binding engagement with the work in an offset and overlapping position comprising a pair of jaws mounted for swinging movement from an open spaced-apart position to a closed abutting position with recesses in each of the jaws extending from a medial plane parallel to the faces of the two jaws to opposite sides of the plane in a direction toward the ends of the jaws, said recesses directing a staple into engagement with the work in an offset overlapping position.

10. In a stapling machine, the combination of a frame, a core in said frame for holding a plurality of staples, a head on said frame surrounding the core and spaced therefrom to allow staples to be moved into the head from the core, a slot in said head adjacent the end of the core for receiving a staple, a staple-driver in said slot, clincher-jaws pivotally mounted on said head for swinging movement to a position below said staple-driver, and a common means for actuating both the staple-driver and clincher-jaws.

11. In a stapling machine, mechanism for successively feeding staples to a driver comprising a frame, a magazine in the frame for holding a plurality of staples, and means bodily movable forwardly and rearwardly in the magazine and so constructed and arranged as to engage the staples and move the whole group forward during its forward movement while adapted to ride over the staples during its rearward movement.

12. In a stapling machine, mechanism for successively feeding staples to a driver comprising a frame, a magazine in the frame for holding a plurality of staples, and a staple-pushers bodily movable forwardly and rearwardly in the maga-

zine, said staple-pushers having resilient fingers adapted to engage the staples and move the whole group forwardly during its forward movement while yielding to slide over the staples during the rearward movement of the staple-pushers.

5

13. In a stapling machine, mechanism for successively feeding staples to a driver comprising a frame, a core in the frame for holding a plurality of staples, a staple-pushers mounted in the frame for longitudinal movement, means for resiliently moving the staple-pushers forwardly, a handle for manually moving the staple-pushers rearwardly, and spring-fingers on the staple-pushers for engaging the staples during its forward movement but adapted to yield and slide over the staples during its rearward movement.

14. In a stapling machine, means for successively feeding staples to a driver comprising a frame, a core in the frame for holding a plurality of staples, guides in the frame on opposite sides of the core, a carriage mounted for longitudinal movement in the frame-guides, a spring for automatically moving the carriage forward, a handle for moving the carriage rearwardly, resilient spring-fingers extending forwardly and at an angle to the carriage and adapted to engage and resiliently urge the staples forwardly but to yield and slide over the staples upon manual retraction of the carriage.

15. In a stapling machine, mechanism for successively feeding staples to a driver comprising a frame, a core in the frame for holding a plurality of staples, and a staple-pushers mounted in the frame for longitudinal movement and having means for engaging the staples during its forward movement but adapted to ride over the staples during its rearward movement, and a detent in the frame for engaging the staples during the rearward movement of the staple-pushers.

16. In a stapling machine, mechanism for successively feeding staples to a driver comprising an enclosing frame having a head at one end and an aperture adjacent its opposite end, a core in the frame for holding a plurality of staples, and a staple-pushers in the frame for moving staples into the head and adapted for rearward movement to engage staples at the end of the core, whereby staples may be placed on the core by insertion through the aperture in the frame without removing the staple-pushers from the frame.

50

17. In a stapling machine, an enclosing frame having a head and operating mechanism for driving staples at one end, and an aperture at the rear and bottom at the other end, a core in the frame for holding a plurality of staples extending into the aperture, a staple-pushers mounted for movement in the frame and adapted to engage the staples during its forward movement but to slide over the staples during its rearward movement, and a detent at the end of the core for holding the staples during the rearward movement of the follower.

18. A portable hand-tool for gathering and binding a plurality of strands comprising a frame having a pair of handles at one end and supporting skids at the opposite end, a staple-driver and clincher-means mounted on the frame, means for successively feeding staples to the staple-driver, and means connected with the handles for simultaneously actuating the staple-driver and the clincher-means.

65

19. In a stapling machine, the combination of a staple-driver for driving staples into engagement with the work to be stapled, clincher-means cooperating with the staple-driver for clinching

75

the ends of the staple, and a pair of cooperating lever handles operatively connected with the staple-driver and the clincher-means, said lever handles being adapted to simultaneously actuate 5 the staple-driver and clincher-means to drive and clinch a staple into binding engagement with the work.

20. In a stapling machine, the combination of a frame having a head at one end, a core in the 10 frame for holding a plurality of staples, a slot in the head for successively receiving staples, a staple-driver in the slot, resilient means for urging the staples along the core and into the slot in the head, and a resilient finger in the slot for 15 yieldingly holding a staple in any position in the slot.

21. In a stapling machine, the combination of a head, a slot in the head, a staple-driver mounted for reciprocation in the slot, means for successively feeding staples to the slot, a resilient finger in the slot for yieldingly holding a staple in any 5 position in the slot, and clincher-jaws pivotally mounted on fixed pivots in the head for swinging movement to a position below said staple-driver to clinch the ends of the staples, said fixed pivots 10 being spaced apart on opposite sides of the staple-driver and independently thereof.
